EDWARD M. JENSEN, OF SEATTLE, WASHINGTON

COLOR LIGHTING DEVICE

Application filed November 7, 1928. Serial No. 317,854.

My invention relates to the art of color lighting devices. More particularly my invention relates to a device for providing a multiple color lighting effect characterized by its intensity of light and compactness.

For purposes of clearness of illustration and description I will describe my invention as applied to stage lighting, but it is to be distinctly understood that my invention is co-extensive with all uses involving like problems and conditions, including window display lighting.

In ordinary theatrical stage lighting there is a forty-two foot border, that is, a forty-two foot stage. In front of this stage there is the grand drape, and back of this grand drape there is commonly provided in successive planes transversely of said stage a series of lights having colored glass mounted beneath said lights to illuminate the stage in different colors. Between each series of lights there are commonly provided scenic curtains or drapes known technically as "teasers". Each series of lights consists of white, blue, amber and red lights, and then this order is repeated throughout the width of the stage so that there may be commonly provided some thirty-six different lights in a given transverse plane. By this means, the stage electrician may, taking his cue from the stage manager, illuminate the stage with the desired color effect during the course of the play. Serious objection obtains to this method of stage lighting in that there is a great number of lights involved and all provision for combining colors is omitted. This arrangement provides only for that quantity of light for a given part of the stage which is receivable from the series of lights directly in the plane above said space.

A primary object of my invention is to reduce the number of lights used and at the same time provide for a plurality of times more lighting effect on a given part of the stage.

A further primary object of my invention is to provide for a combination of colors so that whereas the ordinary thirty-six light sockets provide only fifteen white, seven red and seven blue or seven amber colors (N. B. no

combination of colors), in a stage equipped with the lighting device embodying my invention having only twenty units, that is, twenty light sockets and reflectors, I may provide twenty lights of any single color or twenty combined red and blue, twenty combined red and amber, twenty combined amber and blue, which gives a green effect, or twenty combined red and amber, which gives an orange effect.

The above mentioned general objects of my invention, together with others inherent in the same, are attained by the device illustrated in the following drawings, the same being preferred exemplary forms of embodiment of my invention, throughout which drawings like reference numerals indicate like parts:

Figure 1 is a plan view of a colored lighting device embodying my invention;

Fig. 2 is a view on dotted line 2.2 of Fig. 1;

Fig. 3 is a view on dotted line 3.3 of Fig. 1;

Fig. 4 is a view on dotted line 4.4 of Fig. 1;

Fig. 5 is an enlarged view of the floating frame mounting means of the rack and the associated pinion means; and

Fig. 6 is a view of a modified form of my invention as respects the actuating means for the rack.

In a frame 8, light reflectors 9 are mounted, in which regular lighting sockets 10 and light bulbs 11 may be provided. Below these light bulbs a plurality of colored glass holding frames 12, 13 and 14 are slidably mounted in channel ways 15, 16 and 17. A series of colored panels 18 are disposed at spaced intervals in the colored glass holding frames.

These panels are of a size that will enable them to cover the space beneath a given light, the lights being so spaced that these panels may be disposed in inoperative position between said lights. The panels for a given frame are preferably of a given color and hence in the device illustrated, there being three such colored glass holding frames, there may be panels of three different colors provided, and when the panels are in inoperative position the regular white light may be projected upon the stage without passing through any of the colored panels.

Relative to the means by which the various

racks may be selectively moved into operative position:

To each of the colored glass holding frames, 12, 13, and 14, a link member 19 may be attached, preferably pivotally, and to each such link member a rack 20 is operatively secured. This rack is slidably mounted in a floating frame 21. The floating rack 21 is connected by link members 22 and 23 to rod member 24 to which is operatively connected a solenoid 25. On the other side of the rack there may be disposed similar link members 26 and 27 and rod member 28 and solenoid 29 in all respects similar to the corresponding members on the other side. Operatively mounted with respect to the rack 20 is pinion 30 of a length that may be engaged by racks 31 and 32, disposed beneath rack 20, racks 31 and 32 being similarly connected to their respective colored glass holding frames 13 and 14, precisely as described for colored glass holding frame 12.

Pinion 30 in turn is mounted on shaft 33 on which is secured gear 34 which engages worm 35 on shaft 36, which is operatively connected to a motor not shown. Pinion 30 may be caused to be revolved continuously in one direction. Energizing solenoid 25 will draw inwardly the solenoid core 37, thereby causing rod 24 to move to the right, which would shove frame 21 towards pinion 30 and carries with it the rack 20 slidably mounted therein, so that pinion 30 engages the teeth 38 of rack 20, and if pinion 30 is revolving counter-clockwise, manifestly the colored glass frame 12 would be moved outwardly and cause the colored panels 18 to be disposed beneath the reflectors 9; and when it is desired to retract the panels 18, solenoid 29 may be energized and thereby draw inwardly solenoid core 39, which would actuate frame 21 in the opposite direction to solenoid 25, thereby disengaging the pinion 30 from teeth 38 and causing said pinion to engage teeth 40 on the opposite side of rack 20, and thereby retract the colored glass holding frame 12. Each of the frames 31 and 32, having their separate solenoids, 41 and 42 (on the opposite side solenoids not shown) may be similarly operated. The teeth 38 and 40 extend only part of the length of the rack so that the stopping of the movement of the rack longitudinally is automatic.

Obviously the stage may be supplied with the white light of the uncolored bulbs in reflectors 9 or the stage may be supplied with such colored light as may depend upon the color of the glass in panels 18 of frame 12 or the particular color of the glass in panels of frame 13 or the particular color of the colored glass in panels of frame 14, or any combinations of the panels of these various frames.

Manifestly, in place of the single acting solenoids 25 and 29, a double acting solenoid

may be employed, in order to actuate frame 21 to and from pinion 30.

In Fig. 6, a modified form of mounting and actuating means for rack 20 is illustrated. In this form a bracket 43 is pivotally mounted to oscillate on axis 44. Bracket 43 is provided with a depending arm 45 integrally formed with bracket 43 to the arm 45, and rod 46 is pivotally connected at 47 and at the other end rod 46 is pivotally connected at 48 to a solenoid core 49.

Rack 20 is slidably mounted in guide ways 50, formed in bracket 43. In this manner the actuating of solenoid core 49 swings bracket 43 upon axis 44, thereby causing rack 20 to engage pinion 30.

Obviously, changes may be made in the forms, dimensions, and arrangement of the parts of my invention, without departing from the principle thereof, the above setting forth only preferred forms of embodiment.

I claim:—

1. A device of the character described embodying a light holding frame; a plurality of electric lights therein; a plurality of colored glass holding frames, each frame having panels of glass of a given color for each light; actuating means for said frames consisting of a rack operatively connected to each frame and pinion, said rack and pinion being relatively movable with respect to each other; and means whereby said racks may be selectively engaged by said pinion.

2. A device of the character described embodying a light holding frame; a plurality of electric lights therein; a plurality of colored glass holding frames, each frame having panels of glass of a given color for each light; and actuating means for said colored glass holding frame consisting of a rack operatively connected to each of said frames, a frame having channel engaging ways in which said rack is slidably mounted, a solenoid operatively connected to said frame and a pinion engageable by said racks.

3. A device of the character described embodying a light holding frame; a plurality of electric lights therein; a plurality of colored glass holding frames, each frame having panels of glass of a given color for each light; and actuating means for said colored glass holding frame consisting of a rack operatively connected to each of said frames, a frame pivotally mounted having channel engaging ways in which said rack is slidably mounted, a solenoid operatively connected to said frame, and a pinion engageable by said racks.

4. In a device of the character described, the combination of a plurality of glass holding frames; and a floatingly mounted actuating means comprising a rack for each glass holding frame movably mounted transversely with respect to each of said glass holding

frames and a pinion commonly engageable by each of said racks.

5. In a device of the character described, a colored glass holding frame; and actuating means for said frame embodying a guide frame having channel members, said frame being movably mounted transversely of the longitudinal axis of the said glass holding frame, and a rack frame longitudinally slidably mounted in said guide frame, said rack frame having geared members on each side.

10 6. In a device of the character described, a colored glass holding frame; and actuating means for said frame embodying a guide frame having channel members, said frame being movably mounted transversely of the longitudinal axis of the said glass holding frame, and rack frame longitudinally slidably mounted in said guide frame, said rack frame having geared members on each side, each of said geared members terminating at opposite ends short of the full length of said frame.

15 In witness whereof, I hereunto subscribe my name this 3rd day of November, 1928.

20 EDWARD M. JENSEN.
